CLAIM

The ornamental design for a dispenser for a stack of folded sheets, as shown and described.

DESCRIPTION

FIG. 1 is a perspective view of a dispenser for a stack of folded sheets showing our new design;

FIG. 2 is a front elevation view thereof, the rear elevation view being identical;

FIG. 3 is a right-side elevation view thereof, the left-side view being identical; and,

FIG. 4 is a top plan view thereof.

The broken dash lines in the figures are for illustrative purposes only and represent non-claimed environmental subject matter. Neither the portions of the invention shown in broken dash lines nor the broken dash lines themselves form any part of the claimed invention. The broken dot-dash line in the figures represents the boundary of the claim. Neither the portions of the invention shown outside of the broken dot-dash boundary line nor the broken dot-dash line itself form any part of the claimed invention.
